ATTORNEYS

UNITED STATES PATENT OFFICE.

TILLIE J. ZELTMACHER, OF NEW YORK, N. Y.

DESIGN FOR A LOCKET.

SPECIFICATION forming part of Design No. 28,678, dated May 24, 1898.

Application filed January 27, 1898. Serial No. 668,225. Term of patent 7 years.

To all whom it may concern:

Be it known that I, TILLIE J. ZELTMACHER, of New York city, (borough of Manhattan,) in the county of New York and State of New York, have invented and produced a new and original Design for a Locket, of which the following is a specification, reference being had to the accompanying drawings, forming a part thereof, in which—

Figure 1 is a perspective view of a locket embodying the features of my design. Fig. 2 is a vertical section through the locket, drawn on an enlarged scale; and Fig. 3 is a bottom plan view of the locket, drawn upon a smaller scale.

The design consists in what is characterized

as the body A of the slide, in which is formed a depression B. A frame C surrounds the depression and receives a panel D, appearing transparent. The flange E of the body extends beyond the frame, and the cap member F, connected with the body within the periphery of the flange, is given an interior configuration corresponding to the outer surface configuration of the panel D and frame C. 25

I claim—

The design for a locket herein shown and described.

TILLIE J. ZELTMACHER.
